Fig. 2.

Des. 182,678

PAGE 3

Fig. 3.

Fig.4.

Fig.5.

Fig.6.

Figure 1 is a front perspective view of an ice crusher, showing my new design;

Figure 2 is a rear perspective view;

Figure 3 is a front elevational view;

Figure 4 is a left side elevational view;

Figure 5 is a right side elevational view; and

Figure 6 is a top plan view.

The dominant features of my design reside in those portions thereof shown in full lines.

I claim:

The ornamental design for an ice crusher, as shown and described.
